UNITED STATES PATENT OFFICE.

ARNOLD AUGUST EGLI, OF BERN, SWITZERLAND, ASSIGNOR, BY MESNE ASSIGNMENTS,
TO CHOCOLAT TOBLER HOLDING CO., AKTIENGESELLSCHAFT, OF SCHAFFHAUSEN,
SWITZERLAND.

CANCELING DEVICE.

Application filed January 13, 1923. Serial No. 612,368.

To all whom it may concern:

Be it known that I, ARNOLD AUGUST EGLI, a citizen of the Swiss Republic, residing at Bern, Switzerland, 7 Bitziusstrasse, have invented certain new and useful Improvements in Canceling Devices, of which the following is a specification.

This invention relates in general to canceling devices by which a wrong setting operation in a typesetting machine may be easily canceled immediately after it has been performed. The invention relates more particularly to machines provided with typebars which are adapted to protrude from magazines, as for example machines of the type shown in the copending patent application Serial No. 469,045.

These machines may be provided with registers for registering a row or line of characters written down by means of keys. The registers consist of longitudinally movable members or bars each provided with a series of settable engaging devices. The settable engaging devices are set by the keys with the aid of actuating members mounted on a carrier adapted to travel from register to register through the entire machine. The canceling devices for canceling a registering operation, or for restoring a said settable engaging device to its normal position, may consist of another member, which for convenience will be called a "canceling bar" adapted to travel from register to register through the machine and provided with as many projections or restoring fingers or the like as there are actuating members mounted on the carrier first mentioned. The travelling canceling bar is preferably linked at one end to a rocker bar that extends transversely through the machine and is adapted to be actuated by a "canceling key."

The canceling device may also comprise means for canceling the operation of "changing devices" which are operated to change the normal relation between the type registers or type-position-determining-devices and the typebar moving members, and between the magazine registers or magazine-position-determining-devices and magazine moving members.

A further feature of the invention consists in means for ensuring the proper cancellation of individual registering operations and the common restoration of all settable registering members after they have ful-

filled their functions. This ensuring means consists of members which prevent the longitudinally movable members that carry the settable engaging devices from being shifted in the one direction of their travel when they have been moved out of their initial positions. The manner in which this is accomplished and further details of the invention will appear more fully hereinafter and in the claims and drawings.

Fig. 1 is a vertical section on a line extending from the front to the back of a typebar printing machine provided with canceling devices for canceling the operation of individual type-position-determining-members, changing devices for changing the relation between the registers and the type-moving members, and for canceling all operated magazine-position and type-position-determining members simultaneously.

Fig. 2 is a side view of details of the canceling devices for canceling the operations of individual type-position-determining-members and of a changing device.

Fig. 3 is a side view and partial sectional view of the canceling device by which all of the type-position-determining members are restored together.

Referring to the drawing *b* is a rod which is capable of being reciprocated and provided with projections or strikers *c*¹, *c*², *c*³. The striker *c*² is indicated by dotted lines in a position which it occupies when the rod *b* is moved inwards. A tilting bar *d*¹ which extends transversely through the machine, is also shown in broken lines in the position into which it is tilted by the dotted striker *c*³. *g*¹ is a bar or carrier adapted to be moved transversely through the machine from one magazine register to another, the magazine registers each consisting of a slotted plate *h*¹ with pivoted tappets or engaging members *f*¹ mounted thereon. The transversely movable carrier *g*¹ is provided with an actuating member *e*¹ for each engaging member as *f*¹. Also mounted on the transversely movable carrier *g*¹ is a canceling device consisting of a bar *q*¹ arranged to slide longitudinally on the carrier *g*¹ and provided with a number of upwardly projecting restoring fingers *q*², *q*³. The left hand end of the canceling device *q*¹ is coupled with a rocker bar *q*⁴ which extends transversely through the machine and is adapted to be rocked by a key *q*⁵. When the

105

110

rocker bar q^4 is rocked by depressing the key q^5 the canceling bar q^1 is made to slide to the left as indicated by the arrow in Fig. 2 so that a restoring finger q^2 will restore the 5 operated engaging member f^1 to its initial position.

Thus it will be seen that if a wrong magazine position-determining member or engaging member, as f^1 , is operated, the carrier g^1 which travels transversely through the machine may be moved back one step in the manner well known in writing machines and then the operation of the 10 wrongly actuated engaging member f^1 can be canceled, i. e., this member can be restored to its normal position, by depressing the canceling key q^5 .

The magazine registers are each coupled to a magazine lifting device that consists of 20 a bar n^1 and a lever o^1 which, when the bar n^1 is pulled in the direction of the arrow 2 is adapted to lift a typebar magazine r . A "changing device" consisting of an actuating member e^3 , a coupling member j , and 25 teeth at the free end of a bar l^1 is provided for changing the mechanical relation between each magazine register and magazine lifter. When a rod b is shifted so as to cause its striker c^1 to tilt the tilting bar d^2 30 the actuating member e^3 is swung upwards so as to engage the left hand end of the coupling member j and to cause the hook j^1 of this member to swing downwards. A 35 spring or the like immediately swings the hook j^1 upwards again causing it to engage with the second tooth on the bar n^1 as indicated in Fig. 2. This operation of the changing device can be cancelled by causing the restoring finger q^3 to move to the left and to carry the projection n^{11} and the arm n^1 towards the left so as to cause the hook j^1 40 to slip back into engagement with the second or inner tooth on the link n^1 as shown in Fig. 1. The leftward movement of the 45 restoring finger q^3 is also effected by depressing the canceling key q^5 and thus causing the canceling bar q^3 to slide to the left.

The machine is also provided with typebar 50 registers h^2 and changing devices e^4 each of which latter consists of members like e^4 , j^2 and teeth on the typebar shifters n^2 and which serve to change the relation between the registers h^2 and the typebar shifters n^2 . The top parts of the typebar shifters 55 n^2 are adapted to enter the magazines r and to push the typebars v contained therein out into the printing position.

It will be obvious that the individual canceling devices for canceling the operation of 60 individual typebar position determining members or engaging members f^2 on the typebar registers h^2 , and for canceling the operation of the changing devices which connect the typebar registers to the typebar

shifters n^2 , may be similar to the canceling 65 devices already described above.

The means for simultaneously canceling or restoring a row or series of operated engaging members on different registers consist of common restoring bars, one bar l^3 70 for the magazine register and another bar l^4 for the typebar registers. These restoring bars are adapted to be coupled to the bars l^1 and l^2 by means of the dogs l^5 and l^6 respectively when these bars l^1 , l^2 are shifted 75 in the direction of the arrows 2 for the purpose of cooperating with operated engaging members f^1 , f^2 on the registers so as to raise the magazines r and to push out the typebars v into the positions previously determined 80 by the setting of the engaging members on the registers by means of the depressible keys of the machine.

The free end of the dog l^5 , which, on account of its own weight or of a downwardly 85 pressing spring, tends to swing downward, has a laterally projecting pin or the like which is adapted to slide first on the upwardly inclined surface of a slideway l^7 and then on the downwardly inclined surface 90 of this slideway. Thus, when the magazine operating bar l^1 is shifted to the right, the dog l^5 will be lifted clear of the common restoring bar l^3 and will then be lower again with its hook in the path of the bar l^3 . On the magazine operating bar l^1 being thereupon moved back to the right the hook of the dog l^5 will seize the restoring bar l^3 and carry it towards the right while the registers h^1 with their operated engaging members f^1 will remain in their operated positions until the restoring bar l^3 reaches the operated engaging members and swings them all down into their normal positions. The 100 upwardly projecting portions of the engaging members f^1 are, of course, shaped so as to enable them to move out from between the bars l^3 and l^1 . On the movement of the bar l^1 , with the connected bar l^3 and the dog l^5 , being continued towards the right, the laterally projecting pin on the free end of the dog l^5 will slide upon the left hand inclined surface of the slide way l^7 and the dog l^5 will thus be unhooked from the restoring 105 bar l^3 . The coupling between the restoring bar l^3 and the magazine operating bar l^1 is thus disengaged. The register h^1 is prevented from moving during this restoring operation by means of a ratchet formed on the top of the register and a pawl m^3 . After the engaging members f^1 on the registers have been restored the backwardly moving magazine operating bar l^1 strikes against the lower surface or arm of a pawl-raising member m^1 and thus turns it in a counter-clockwise direction so as to cause its upwardly extending arm to raise the pawl m^3 into the 110 position shown in Fig. 1 in which it is clear 115 120 125

of the ratchets on the registers. When the magazine operating bar l^1 was moved forward to the left it tilted the pawl-operating member m^1 clockwise and thus caused it to permit the pawl m^3 to drop into engagement with the register ratchets as indicated in Fig. 3.

Similar common restoring devices to those which have been described for the magazine registers can, of course, also be used in connection with the typebar registers.

The simultaneous restoration of the registers could also be accomplished by a fixed common restoring bar l^3 if the registers h^1 or h^2 were arranged to execute a short movement to the left after the typebars have been moved into the printing position. This short leftward motion could be produced by shifting the bar or pawl m^3 to the left so as to cause the upwardly extending portions of the actuating members f^1 to strike against the fixed common restoring bar l^3 . The same results could be obtained if the registers h^1 , h^2 were first returned to normal and the common restoring bar l^3 were then moved towards the right.

I claim:

1. In a machine for producing a line of characters, typebars, a plurality of members equipped with settable engaging devices and adapted for determining the positions of the typebars, means for actuating the settable engaging devices, means for operating a set engaging device, and means for restoring an actuated engaging device before it is operated.

2. In a machine for producing a line of characters, typebars, a plurality of members equipped with settable engaging devices and adapted for determining the positions of the typebars, means for actuating the settable engaging devices and consisting of a device adapted to travel from one said member to another, and a restoring means associated with the said device and travelling therewith and adapted for restoring an actuated engaging device.

3. In a machine for producing a line of characters, typebars, a plurality of members equipped with settable devices, means dependent on the settable devices and adapted for determining the setting of the typebars in their printing position, means for changing the relation between the determining means and the settable devices, actuating means for setting the settable devices, operating means for operating the set settable devices, and means for restoring the settable devices and the relation between the determining means and the settable devices before the operation of the set settable devices.

4. In a machine for producing a line of characters, typebars, a plurality of registers equipped with settable engaging devices and adapted for determining the positions of

the typebars, means for actuating the settable engaging devices and adapted to travel from one register to another, means for operating a set engaging device, restoring means associated and travelling with the actuating means and adapted for restoring an actuated engaging device before it is operated, and a controlling member for controlling the restoring means and adapted to move in a direction at right angles to the motion of the restoring means.

5. In a machine for producing a line of characters, typebars, movable registers with engaging members for determining the positions of the typebars, actuating members for actuating the engaging members, an operating means adapted to cooperate with actuated engaging members and to shift the registers and to move the typebars into a printing position, and means for restoring all actuated engaging members simultaneously, said restoring means comprising locking means for preventing motion of the registers after the printing position has been established, and a member adapted to be moved against the engaging members, while the registers are locked.

6. In a machine for producing a line of characters, typebars, movable registers with engaging members for determining the position of the typebars, actuating members for actuating the engaging members, an operating bar adapted to cooperate with actuated engaging members and to shift the registers and to move the typebars into a printing position, a restoring bar for restoring actuated engaging members; a dog on the operating bar, and means for bringing the dog into and out of engagement with the restoring bar.

7. In a machine for producing a line of characters, typebars, movable registers with engaging members for determining the position of the typebars, actuating members for actuating the engaging members, an operating bar adapted to cooperate with actuated engaging members and to shift the registers and to move the typebars into a printing position, a restoring bar for restoring actuated engaging members; a dog on the operating bar, means for bringing the dog into and out of engagement with the restoring bar, and a locking bar for locking the registers after the typebars have been shifted into the printing position and until the actuated engaging members have been restored.

8. In a machine for producing a line of characters, typebars, movable registers with engaging members for determining the position of the typebars, actuating members for actuating the engaging members, an operating bar adapted to cooperate with actuated engaging members and to shift the registers and to move the typebars into

a printing position, a restoring bar for restoring actuated engaging members, a dog on the operating bar, means for bringing the dog into and out of engagement with the restoring bar, a locking bar for locking the registers after the typebars have been shifted into the printing position and until the actuated engaging members have been restored, and means for restoring the locking bar into 10 its non-locking position during the return movement of the operating bar.

9. In a machine for producing a line of characters, typebars, movable registers with engaging members for determining the position of the typebars, actuating members for actuating the engaging members, an operating bar adapted to cooperate with actuated engaging members and to shift the registers and to move the typebars into a printing 15 position, a restoring bar for restoring actuated engaging members, a dog on the operating bar, means for bringing the dog into and out of engagement with the restoring bar, a locking bar for locking the registers 20 after the typebars have been shifted into the printing position and until the actuated engaging members have been restored, and a three-armed pivoted member for operating the locking bar, the one arm being adapted 25 to cooperate with the said operating bar during its forward movement and the other being adapted to cooperate with the operating bar during its return movement.

10. In a type-setting-printing machine, 30 type carriers, a member equipped with settable engaging devices and adapted for determining the position of a type carrier, means for actuating the settable engaging devices, means whereby the position of a type carrier is located by said set engaging device, and means for restoring an actuated 35 engaging device before said type carrier is located thereby.

11. In a typesetting printing machine, 40 magazines, type-carriers in the magazines, magazine registers and typeregisters for registering the positions into which the types are to be moved, means for moving the magazines and type-carriers, actuating means for 45 effecting registrations on the said registers, and canceling means for canceling a said registration prior to the operation of the said moving means.

12. In a typesetting printing machine, 50 magazines, type-carriers in the magazines, magazine registers and type registers for registering the positions into which the types are to be moved, means for moving the magazines and type-carriers, changing means for 55 changing the relation between type registers and the moving means, actuating means for 60

effecting registrations on the said registers, and canceling means for canceling a said registration and the operation of the changing means prior to the operation of the said 65 moving means.

13. In a typesetting printing machine, 70 magazines, type-carriers in the magazines, magazine registers and type registers for registering the positions into which the types are to be moved, means for moving the magazines and the type-carriers, changing means for changing the relation between registers and the moving means, actuating means for effecting registrations on the said registers, 75 and canceling means for canceling a said registration prior to the operation of the said moving means.

14. In a typewriter, type bars, a member 80 equipped with settable engaging devices and adapted for determining the position of a type bar, means for actuating the settable engaging devices, means whereby a type bar is located by a set engaging device, and means for restoring an actuated engaging 85 device before the type bar is located thereby.

15. In a typewriter, magazines, type bars 90 in the magazines, magazine registers and type registers for registering the positions into which the types are to be moved, means for moving the magazines and type bars, actuating means for effecting registrations on the said registers, and canceling means for canceling a said registration prior to the operation of the said moving means. 95

16. In a typewriter, magazines, type bars 100 in the magazines, magazine registers and type registers for registering the positions into which the types are to be moved, means for moving the magazines and typebars, changing means for changing the relation between type registers and the moving means, actuating means for effecting registrations on the said registers, and canceling 105 means for canceling a said registration and the operation of the changing means prior to the operation of the said moving means.

17. In a typewriter, magazines, type bars 110 in the magazines, magazine registers and type registers for registering the positions into which the types are to be moved, means for moving the magazines and the type carriers, changing means for changing the relation between registers and the moving means, actuating means for effecting registrations 115 on the said registers, and canceling means for canceling a said registration prior to the operation of the said moving means.

In testimony whereof I have affixed my signature.

ARNOLD AUGUST EGLI.
